DISPENSER

Herman Carew, Easton, Pa., assignor to Dixie-Vortex Company, Easton, Pa., a corporation of Delaware

Application July 25, 1936, Serial No. 92,636

4 Claims. (Cl. 312—43)

My invention relates to new and useful improvements in dispensers and more particularly to a dispenser for supporting a stack of nested articles, such as paper cups or similar containers, 5 and permitting the ready withdrawal of the terminal article.

The principal object of the invention resides in the provision of a casing or housing of cylindrical form provided with inwardly projecting portions, the upper edges of the inwardly projecting portions forming ledges upon which an outwardly directed flange or bead of the terminal article or container is supported to in turn support the stack, the inner faces of the inwardly projecting portions being devoid of curves and merging with the circumference of the casing or housing.

A further object of the invention resides in the provision of a casing or housing having interior projections, said projections supporting a stack 20 of articles such as paper cups or like containers but permitting withdrawal of the terminal article by temporarily distorting the mouth portion thereof.

Another object of the invention resides in the provision of a dispenser including a cylindrical casing or housing in which a stack of nested articles are adapted to be supported, novel means being provided for supporting said casing or housing, and the interior diameter thereof being obstructed by inwardly directed projections forming intermediate the ends of the casing or housing portions adapted to support the stack of nested articles but permitting withdrawal of the terminal article by a temporary distortion of a portion 35 thereof.

Still another object of the invention resides in the provision of an adapter to permit the support of articles of a less diameter than those normally adapted to be supported by the casing 40 or housing.

With the above and other objects in view, which will appear as the description proceeds, my invention consists in the novel details of construction and arrangement of parts described in the following specification and illustrated in the accompanying drawings, and while I have illustrated and described the preferred embodiments of my invention, as they now appear to me, it will be understood that such changes may be made as will fall within the scope of the appended claims.

In the drawings:—

Fig. 1 is a rear face view of one embodiment of my invention.

Fig. 2 is a transverse vertical section with parts shown in elevation.

Fig. 3 is a horizontal section on the line 3—3 of Fig. 1 looking in the direction of the arrows.

Fig. 4 is a horizontal section on the line 4—4 5 of Fig. 2, looking in the direction of the arrows, and showing a top plan of an article being withdrawn.

Fig. 5 is a side elevation of another form of my invention including a casing or housing and 10 an enclosing dome.

Fig. 6 is a rear elevation of the casing or housing shown in Fig. 5.

Fig. 7 is a horizontal section on the line 7—7 of Fig. 5 looking in the direction of the arrows. 15

Fig. 8 is a top plan of the casing or housing shown in Fig. 5.

Fig. 9 is a section on the line 9—9 of Fig. 8.

Fig. 10 is a bottom plan of the casing or housing shown in Fig. 8.

Fig. 11 is a section similar to Fig. 9 with my improved adapter ring in position.

Fig. 12 is a side elevation of the adapter ring; and

Fig. 13 is a bottom plan of the adapter ring. 25

In Figs. 1 to 4 inclusive of the drawings I have shown a dispenser which is primarily intended for home use, of relatively small size, and adapted for supporting a relatively short stack of the nested articles.

In Figs. 5 to 13 of the drawings I have illustrated a dispenser for supporting a longer stack of the nested articles and in this form of the invention I provide a base portion, preferably of Bakelite or similar material, which I will term 30 a casing or housing, adapted to be secured to a wall or other support, and this casing or housing, which forms a base, in turn supports a glass dome, which is removable, adapted for enclosing the upper portion of the stack.

The form of dispenser illustrated in Fig. 1 is formed of Bakelite or similar material, and includes the cylindrical body portion indicated at 1 and the cap or closure 2 adapted for closing the upper end of the body portion, as shown more 45 particularly in Fig. 2 of the drawings, the cap being telescoped over the upper end of the body. What might be termed the rear wall of the body is provided with the outer flanges 3 and 4, and the inner flanges 5 and 6, a dove-tail tapered 50 groove 7 being formed between the flanges 5 and 6 for receiving a metal bracket 8, as shown more particularly in Fig. 4 of the drawings, this metal bracket being secured to a wall or similar support by means of the screws 9 or other suitable 55

fastenings which pass through the openings 10 formed in the bracket. It will be noted that the outer faces of the flanges 3, 4, 5 and 6 engage the face of the wall or support and when desired the bracket 8 may be dispensed with and the dispenser secured to the wall or support, particularly where the same is of a tile or like material, by applying cement or other adhesive to the edges of the flanges 3, 4, 5 and 6.

10 Interiorly the body portion 1 is provided with the oppositely disposed projections 11 and 12 and 13 and 14 and these projections, at their upper edges, form shoulders 15 for supporting the stack of nested articles, one of the articles being shown at 16 and provided with the outwardly directed bead or flange 17, at its mouth portion, this bead or flange engaging the shoulders 15 of the projection as shown more particularly in Fig. 2 of the drawings. The terminal article or cup 16 has its lower end projecting below the end of the body 1 in convenient position to be grasped by a person desiring to withdraw the same. As the terminal article is withdrawn by a downward movement the mouth portion of the article will be distorted as shown more particularly in Fig. 4 of the drawings but will return to its normal shape when entirely removed. The interior projections 11 and 12 and 13 and 14 intersect a pair of right angularly extending diameters of the body 1, which forms a casing or housing, and the inner faces thereof are flat and devoid of curves and merge with the circumference of the casing. It will therefore be seen that these projections, which in the form of the invention shown in Figs. 1 to 4 inclusive of the drawings, extend to the lower end of the casing or housing are perfectly flat or smooth, so to speak, and form a smooth bearing over which the distorted portions of the article ride. I wish to call particular attention to the fact that the projections shown intersect a pair of right angularly extending diameters of the casing or housing, the outer faces merge with the circumference of the casing or housing, and there are provided the flat surfaces over which the distorted portions of the article being withdrawn ride.

In Figs. 5 to 13 inclusive of the drawings, as previously stated, I provide a casing or housing indicated generally at 18 which forms a base for supporting a glass dome 19 which encloses the stack of nested articles, one of these articles being shown in dotted lines at 20. This base or casing is preferably formed of Bakelite or similar material. A metal ring 21 surrounds the lower end of the dome 19 and carries the pins or projections 22 which are adapted to be received in the bayonet slots 23 formed in a metal ring 24, positioned on the upper end of the casing or housing 18. This casing or housing 18 is provided on its rear portion with a dove-tail projection 25 adapted to be received in a dove-tail groove formed in a bracket 26 secured to a wall or other support by means of the screws 27 or other suitable fastenings.

65 Interiorly the casing or housing 18 is formed with the oppositely disposed projections 28 and 29 and 30 and 31 which provide a support for a stack of the articles 20, an outwardly directed bead or flange 32 of the terminal article resting upon the upper surfaces or edges of the projections as shown more particularly in Fig. 9 of the drawings. The inner faces of the projections are flat and devoid of curves and merge with the circumference of the casing. These smooth inner 70 faces of the projections form surfaces over which

the beaded or flanged portions of the articles ride as they are withdrawn from the stack, it being understood that in withdrawing the mouth portion of the article will be distorted similar to that disclosed in Fig. 4 of the drawings. At the same time it will be understood that the terminal article will project below the end of the casing or housing as shown in position to be readily grasped by the user. The projections 28 and 29 and 30 and 31 of that form of the invention illustrated in Figs. 5 to 13 of the drawings differ from the projections 11 and 12 and 13 and 14 in that they do not extend to the lower end of the casing or housing but are relatively short and are positioned intermediate the ends of the casing or housing as shown more particularly in Fig. 9 of the drawings.

In order to adapt that form of the invention shown in Figs. 5 to 13 inclusive of the drawings for articles of varying diameters I provide what might be termed an adapter or adapter ring. This adapter or adapter ring is shown in Figs. 12 and 13 of the drawings and in position within the casing or housing in Fig. 11. The adapter, shown at 33 is cylindrical in form and interiorly is provided with oppositely disposed projections 34 and 35 and 36 and 37, shown more particularly in Fig. 13 of the drawings, which form shoulders at their upper ends at 38 to support the stack of nested articles as shown more particularly in Figs. 11 and 12 of the drawings. The terminal article of the stack is shown at 39 and is provided with an outwardly directed bead or flange 40 which rests on the shoulders of the projections. These projections 34 and 35 and 36 and 37 are similar to the projections 11 and 12 and 13 and 14 of the form of the invention disclosed in Figs. 1 to 4 inclusive in that they extend to the lower end of the adapter ring. The projections of the adapter or adapter ring are arranged similarly to those shown in Figs. 1 to 4 and their inner faces are devoid of curves and merge with the circumference of the ring. Therefore, the inner faces form smooth surfaces over which the lip or flange portion of the article is withdrawn. It will be understood that in withdrawing the terminal article, which normally projects below the end of the adapter ring, the mouth portion will be distorted as shown in Fig. 4 of the drawings.

50 Exterioly the adapter or adapter ring is provided with the flattened portions indicated at 41 which provide recesses to receive the projections 28 and 29 and 30 and 31 formed interiorly of the casing or housing 18. When the adapter or adapter ring is used a stack of articles of less diameter than those normally supported by the projections 28 and 29 and 30 and 31 may be supported. Suitable adapters or adapter rings may be used for supporting the articles of desired diameters.

From the above detailed description it is thought that the construction of the two forms of dispenser shown will be clearly understood and it is not thought necessary to go further 65 into detail. While I am aware that ledges or projections have been provided in dispensers for supporting a stack of nested articles and permitting the withdrawal of the terminal article at the same time it is new with me to provide 70 the projections of the specific formation described wherein an abrupt supporting shoulder is provided, their inner faces merge with the circumference of the casing or housing, and their inner faces provide smooth surfaces, devoid of 75

any curves or the like, over which the mouth portion of the article rides as the article is withdrawn from the stack. At the same time it is new with me to provide an adapter or adapter ring of the character disclosed and described.

Having fully described my invention what I claim as new and desire to secure by Letters Patent is:—

1. In a dispenser, the combination with a casing having interior projections adapted to support a stack of nested articles of a given diameter, of a ring-like member adapted to be inserted into the casing and supported by the projections, said member having interior projections adapted to support a stack of nested articles of less diameter.

2. In a dispenser, the combination with a casing having oppositely disposed interior projections adapted to support a stack of nested articles of a given diameter, of a ring-like member adapted to be inserted into the casing and supported on the interior projections thereof, said member having oppositely disposed interior pro-

jections adapted to support a stack of nested articles of less diameter.

3. In a dispenser, the combination with a casing having oppositely disposed interior projections adapted to support a stack of nested articles of a given diameter, of a ring-like member adapted to be inserted into the casing, said member having exterior portions to receive the interior projections of the casing and be supported thereby and oppositely disposed interior projections adapted to support a nested stack of articles of less diameter.

4. In a dispenser, the combination with a casing having interior projections adapted to support a stack of nested articles of a given diameter, of a ring-like member adapted to be inserted into the casing, said member having exterior portions to receive the interior projections of the casing and be supported thereby and interior projections adapted to support a nested stack of articles of less diameter.

HERMAN CAREW.
